UNITED STATES PATENT OFFICE.

JOHN J. STEINBACH, OF SCRANTON, PENNSYLVANIA, ASSIGNOR TO WILMOT ENGINEERING COMPANY, OF HAZLETON, PENNSYLVANIA, A CORPORATION OF PENNSYLVANIA.

COAL JIG.

1,427,651.

Specification of Letters Patent. Patented Aug. 29, 1922.

Application filed May 5, 1920. Serial No. 379,007.

To all whom it may concern:

Be it known that I, JOHN J. STEINBACH, a citizen of the United States, and a resident of Scranton, in the county of Lackawanna and State of Pennsylvania, have invented an Improvement in Coal Jigs, of which the following is a specification.

My invention relates to coal jigs and it has for its object to provide an improvement in the means for co-acting and co-operating with the rotating means which supports the jig pan of a coal jig or other like apparatus to produce a combined reciprocating and oscillatory motion; that is, a gyratory motion. More specifically, my invention has for its object to provide an improvement in the means for holding and guiding the movements of the lower ends of the bars or like devices by means of which the jig pan is supported upon eccentrics or other actuating means upon the actuating shaft, the said ends terminating a distance below the said pan. By thus holding the lower ends of said bars or other like devices, or by otherwise holding the jig pan, rotation of the said eccentrics or equivalents therefor upon and from which the jig pan is suspended, a gyratory movement of the said pan is effected.

I have not undertaken to set forth and enumerate all of the objects and advantages of my invention, but these will be pointed out in the detailed description thereof which follows or will be apparent from such description.

In order that my invention may be readily understood and its practical advantages comprehended and fully appreciated, reference may be had to the accompanying drawing in which I have illustrated one form of embodiment thereof. It will be understood, however, that changes in the details of construction may be made within the scope of the claims without departing from my said invention.

In the drawing:

Fig. 1 is a longitudinal, sectional view of a portion of a coal jig apparatus taken on the line 1—1 of Fig. 2 and embodying my invention; and

Fig. 2 is a transverse, sectional view taken on the line 2—2 of Fig. 1.

Referring to the drawing: 1 designates the bottom members, 2 the upright end members and 3 the side members of a frame structure upon which the operative parts of a jig

structure are supported. 4 designates the side and bottom walls of a portion of a sheet metal tank which is adapted to hold water.

5 designates a jig pan situated in the upper portion of the said tank and into which a mixture of coal, slate, etc. is adapted to be discharged and in which the coal is separated from the slate, rock and other matter, which, if allowed to remain therein, would be objectionable.

For a full description of a coal jig of the character indicated herein and of parts associated with the jig pan, reference may be had to United States patent to Henry W. Falker, No. 1,055,731, granted March 11, 1913.

The opposite sides of the jig pan 5 are secured to bars 6 which are connected with eccentric straps 7 supported upon eccentrics 8, which in turn are supported upon a shaft 9. The bars 6 are extended beyond the lower side of the jig pan 5 and such extensions are braced by means of the inclined brace bars 10, the upper ends of which are secured by rivets to the opposite sides of the jig pan and their lower, inner ends to the lower end portions of the supporting bars 6. 12 designates holding and guiding bars pivotally supported at their outer ends upon the inner ends of adjustable screw threaded rods 13. The inner end of each of the bars 12 is bifurcated as indicated to form a clevis 14, the opposite sides of which are situated upon the opposite sides of the lower ends of the bars 6 and 10. The opposite sides of the said clevis at their inner ends are provided with perforations which are in alignment with perforations through the lower end portions of the bars 6 and 10, and the several parts 6, 10 and 14 are secured together by means of a bolt 95 or clevis pin 16 extending therethrough. It will be seen, therefore, that the inner ends of the holding and guiding bars 12 are pivotally connected to the lower end portions of the bars 6 and 10.

In the construction shown, the adjustable screw threaded rods 13 extend through the end wall and a cross tie 17 extending between the end posts 2 at one end of the frame structure and are adjustably secured and held in position thereon by means of the wedge-shaped washers 18 and the nuts 19.

It will be observed that in the construction as shown the jig pan 5 is slightly tilted. If

desired the position of the jig pan with respect to a horizontal plane may be varied by adjusting the screw threaded rods 13. Such adjustment may be effected by adjusting the nuts and washers 18 and 19. By adjusting these screw threaded rods outwardly, the tilt of the jig pan would be increased, and by adjusting them inwardly the tilt not only would be decreased but if desired, the adjustment may be extended to a point to cause a tilting of the jig pan in the opposite direction from that in which it is shown in Fig. 1 of the drawing.

Although, as illustrated in the drawing, each of the bars 6 is extended and the inner swinging ends of the rods or bars 12 are connected to the respective lower end portions thereof, yet it will be understood that other means than that shown may be provided for operatively connecting the inner ends of the said rods or bars to the jig pan to hold and more or less guide the latter and to co-operate with the eccentrics or other actuating means upon the shaft 9 to effect gyratory motion of the said pan.

Although I have shown the upper ends of the bars 6 as being supported upon and suspended from eccentrics 8, it will be understood that other means may be provided for effecting actuation of the said bars and causing the desired and required motion of the jig pan.

In the operation of the jig, it will be apparent that as the jig pan 5 is raised and lowered by means of the bars 6, the inner ends of the rods or bars 12 move through the arcs of circles, causing a like movement of the lower ends of the bars 6.

The means provided by me for holding and guiding the lower ends of the bars 6, or such other means as may be substituted therefor, is very durable and, as is obvious, is positive in its action and possesses the further advantage of adjustment to vary the angular position of the jig pan as above described.

Although I have employed the term "coal jig" in connection with this description, I

desire it to be understood that this term is intended to comprehend the apparatus not only for the washing and separation of coal from slate, but also for the washing and separation of ores of various kinds.

The term "eccentric means" employed in the claims is intended to cover not only the eccentrics 8 illustrated in the drawing, but also cranks or crank pins which might be employed to effect the same motion of the jig pan as is effected by the eccentrics.

I claim:

1. In a jig structure, the combination of a tank, a rotatable shaft supported above said tank, said shaft being provided with eccentrics, bars supported upon and suspended from the said eccentrics and extending into the said tank, a jig pan rigidly secured to intermediate portions of said bars, holding and guiding rods having adjustable connection at their outer ends to a wall of the said tank, the said rods extending inwardly and downwardly, and having connection at their inner ends with portions of the said bars a distance below the said jig pan and the inner portions of said holding and guiding rods having pivotal connections with the outer portions thereof, substantially as described.

2. In a jig structure, the combination of a tank which is adapted to hold water, a rotatable shaft situated above the said tank and being provided with eccentrics, bars supported upon and suspended from the said eccentrics, said bars extending into the said tank and terminating a distance above the bottom thereof, a jig pan having its opposite sides secured to intermediate portions of the said bars, holding and guiding rods connected at their inner ends to the lower end portions of said bars and means adjustably secured to a wall of the said tank for pivotally and adjustably connecting the said rods to said wall, substantially as described.

In testimony that I claim the foregoing as my invention, I have hereunto signed my name this 17th day of February A. D., 1920.

JOHN J. STEINBACH.
